CLAIM

The ornamental design for a milk frother as shown and described.

DESCRIPTION

FIG. 1 is a top-left perspective view illustrating the design for a milk frother.

FIG. 2 is a front view thereof.

FIG. 3 is a rear view thereof.

FIG. 4 is a left-side view thereof.

FIG. 5 is a right-side view thereof.

FIG. 6 is a top view thereof; and,

FIG. 7 is a bottom view thereof.

The broken lines in FIGS. 1-7 show portions of the article that form no part of the claimed design.

1 Claim, 6 Drawing Sheets
